UNITED STATES PATENT OFFICE

153,776

DESIGN FOR A SALVAGE HOOK

Harry J. Eimmerman, New Haven, Conn.

Application May 11, 1948, Serial No. 146,281

Term of patent 14 years

(Cl. D54—13)

To all whom it may concern:

Be it known that I, Harry J. Eimmerman, a citizen of the United States, residing in New Haven, in the county of New Haven and State of Connecticut, have invented a new, original, and ornamental Design for Salvage Hooks, of which the following is a specification, reference being had to the accompanying drawing, forming parts thereof, in which:

Fig. 1 is a side elevational view of a salvage hook embodying my new design;

Fig. 2 is a front elevational view thereof;

Fig. 3 is a top plan view thereof; and

Fig. 4 is a sectional view on line 4—4 of Fig. 1.

I claim:

The ornamental design for a salvage hook, substantially as shown.

HARRY J. EIMMERMAN.
